UNITED STATES PATENT OFFICE.

CHARLES J. RAUCH, OF MEMPHIS, TENNESSEE.

DESIGN FOR A BUTTON.

53,376.

Specification for Design.

Patented May 27, 1919.

Application filed May 13, 1918. Serial No. 234,330. Term of patent 14 years.

To all whom it may concern:

Be it known that I, CHARLES J. RAUCH, a citizen of the United States of America, and a resident of Memphis, in the county of Shelby and State of Tennessee, have invented a new, original, and ornamental Design for a Button, of which the following is a specification, reference being had to the accompanying drawing, forming part hereof.

In the drawing, Figure 1 is a perspective view of a button showing my design.

Fig. 2 is an elevation.

I claim:

The ornamental design for a button as shown.

CHARLES J. RAUCH. [L. S.]
